UNITED STATES PATENT OFFICE.

MICHAEL JAMES O'LEARY, OF GREEN BAY, WISCONSIN.

STEAM-BOILER.

SPECIFICATION forming part of Letters Patent No. 443,786, dated December 30, 1890.

Application filed September 9, 1890. Serial No. 364,418. (No model.)

To all whom it may concern:

Be it known that I, MICHAEL JAMES O'LEARY, a citizen of the United States, residing at Green Bay, in the county of Brown 5 and State of Wisconsin, have invented certain new and useful Improvements in Steam-Boilers; and I do hereby declare the following to be a full, clear, and exact description of the invention, such as will enable others skilled in 10 the art to which it appertains to make and use the same.

My invention relates to improvements in multitubular return-flue steam-boilers, and more particularly to that class known as "up-right" or "vertical" return-flue boilers.

The object of my invention is to provide means for furnishing such boilers with a triple return of the fire and heat through the boiler, and to arrange combustion-chambers 20 therein for thoroughly consuming the products of incomplete combustion and more thoroughly utilizing the heat by retarding its escape to the smoke-stack.

It is also my object to construct such a 25 boiler in a form as compact as possible, one that will generate steam economically and rapidly and produce a greater power to a given size of boiler.

It is also my object to construct a boiler in 30 which all the parts subjected to direct fire and heat contact shall be protected by water, so as to insure increased longevity to the parts so exposed.

In the drawings forming a part of this 35 specification, Figure 1 is a vertical section, and Fig. 2 is horizontal section taken on the line X X of Fig. 1.

Reference being had to the drawings, S denotes the shell of the boiler, and W L the 40 water-line.

A denotes the furnace or fire-box arranged under the boiler and connected with the boiler-shell by stay-bolts *a* and water-leg.

G denotes the grate.

B B B denote the main flues, through which 45 the complete and incomplete products of combustion pass from the furnace or fire-box to the combustion-chamber C.

E E E E are main flues connecting the 50 combustion-chamber C with the combustion-chamber D.

F are smaller flues communicating with the smoke-stack.

The furnace opens at the rear into the main flues B B B.

The chamber D is braced by stay-bolts *s* to the fire-box and shell, leaving a water-space between them. Said chamber is semicircular in shape and its upper wall forms the lower tube-sheet for the tubes F.

The combustion-chamber C is connected by braces *c* and stay-bolts *c'* to the boiler-shell, leaving a water-space between them. Said chamber is semicircular in shape, the main tubes B B B and E E E opening into the 65 same, as shown in Fig. 2. Said combustion-chambers D and C are constructed with doors conveniently arranged for cleaning purposes.

It will be seen that by my construction the furnace or fire-box has a water-space over the 70 top and in rear of its back walls, and the combustion-chambers C and D are also surrounded by water, as likewise the main flues B B B and E E E and smaller flues F.

The fire being started in the furnace or fire-box, the products of complete and incomplete combustion pass through the main flues B B B to the combustion-chamber C, where the incomplete products of combustion are consumed, and such of said products as escape 80 are carried through the main flues E E E E to the combustion-chamber D, where they are also consumed, thus giving perfect fuel combustion. It is evident that said combustion-chambers C and D also serve to retain and 85 distribute the heat and more effectually utilize the same by retarding its escape to the smoke-stack.

It will be noticed that by my construction the last series of flues F leading to the 90 chimney consist of tubes of comparatively very small diameter, the object of which is to more effectually retard the escape of the incomplete products of combustion from the chamber D, besides giving a greater vertical 95 heating-surface in the boiler. Again, by my construction the combustion-chambers occupy a greater longitudinal than vertical heating-surface, thereby more effectually retarding and consuming the products of incomplete 100 combustion, giving a greater steam-space at the top of the boiler, placing the heating-surf-

face lower down in the boiler and causing a better circulation of water therein. Again, by my construction the combustion-chambers and main flues are below the water-line of the boiler and surrounded on all sides by water. Again, by my arrangement the fire-box is given a greater longitudinal heating-surface.

Having shown and described my invention, what I claim, and desire to secure by Letters Patent, is—

1. In an upright tubular-boiler, the combination and arrangement of the small tubes F, lower combustion-chamber D, flues E, combustion-chamber C, and flues B, substantially as shown and described.

2. In an upright triple-return-flue boiler, the arrangement herein shown and described of the fire-box A, an upper combustion-chamber C, and a lower combustion-chamber D,

said fire-box and chambers having a maximum of longitudinal heating-surface.

3. An upright triple-return-flue boiler consisting of main tubes B B B, leading to an upper combustion-chamber C, the main flues E E E, leading from said chamber to a larger combustion-chamber D arranged below, all of said chambers and flues or tubes placed below the water-line of the boiler, and a series of flues F, of minimum diameter, leading from said chamber D to the smoke-stack, substantially as and for the purposes shown and described.

In testimony whereof I affix my signature in the presence of two witnesses.

MICHAEL JAMES O'LEARY.
